REINHOLD S. BECKER, OF ROCHESTER, NEW YORK, ASSIGNOR TO EASTMAN KODAK COMPANY, OF ROCHESTER, NEW YORK, A CORPORATION OF NEW YORK.

MARKING PHOTOGRAPHIC PAPER.

1,210,400.

Specification of Letters Patent. Patented Jan. 2, 1917.

Application filed June 22, 1915. Serial No. 35,716.

To all whom it may concern:

Be it known that I, REINHOLD S. BECKER, of Rochester, in the county of Monroe and State of New York, have invented certain new and useful Improvements in Marking Photographic Paper; and I do hereby declare the following to be a full, clear, and exact description thereof, reference being had to the accompanying drawing and to the reference-numerals marked thereon.

My present invention relates to photography and more particularly to photographic paper and it has for its object to provide a method of placing identifying marks upon the body of the paper of such a nature that they will not be obtrusive or, in fact, easily discernible but, on the other hand, quite invisible by either reflected or transmitted light, except under certain conditions, so that ordinarily paper bearing the mark will have the usual blank appearance.

A further object is to so mark the paper that it will not interfere in any way with the photographic properties thereof.

To these and other ends the invention resides in certain improvements and combinations of parts all as will be hereinafter more fully described, the novel features being pointed out in the claims at the end of the specification.

In the drawings: Figure 1 is a plan view of the reverse side of a sheet of photographic paper marked in accordance with this invention, the mark being invisible from this point of view; Fig. 2 is a perspective view of the sheet showing the same side of the paper as viewed from an angle at which the mark becomes visible, and Fig. 3 is a sectional view of the sheet.

Similar reference numerals throughout the several figures indicate the same parts.

It has been found desirable to place an identification mark on photographically sensitized paper as a means, for instance, of distinguishing a particular brand from other similar brands, whereby the user thereof may know as to its characteristics and so that it will be difficult for a commercial photographer who makes prints for the amateur to substitute another paper for the one called for. The thicker papers, such as post cards, may have black ink printing applied on their backs, but this method is not usable with the lighter weights of paper, for one reason because of the mark

showing through in the finished picture. Furthermore, the user of photographic paper is likely to object to advertising marks appearing boldly on the rear of the paper, even if it does not show through. For like reasons, water marks, being thin spots in the paper, are considered objectionable.

The object of my invention, as before stated, is to mark the back of photographic paper in such a manner that the marking will not be visible on the face or objectionably noticeable on the back thereof, and the material used will not affect the sensitive emulsion.

In ordinary printing operations, an ink is preferred which gives the maximum contrast with the color of the paper. According to my method, I print the paper with an ink which so matches the back of the paper in color, as to be substantially invisible on the opposite side of the paper from the printing, and only visible on the same side by reflected light, which passes from the paper to the eye within a given angular range. Furthermore, this ink used for printing the designation on the paper is of such a chemical nature that it will not injuriously affect the sensitive emulsion on the other side of the paper or that of another paper placed in contact with it in the pack.

In the drawings, I have shown in Fig. 1 a plan view of a sheet of ordinary photographic paper that has been marked in accordance with my invention and which comprises a paper backing or base 1 on the front of which is the sensitized body or layer of photographic emulsion. Looking directly at the sheet with the line of vision at right angles to the plane of the paper, as in Fig. 1, the mark is invisible, but when the sheet is tilted before the eye with the light coming from the far side so that the angle of incidence is acute, the mark becomes visible, as shown in Fig. 2, providing the eye is in proper alignment at the similar angle of reflection. This is because the inked surface of the area covered by the impression gives a distinguishably different optical reflection from the surrounding plain paper surface. The mark shown in the present instance is a combination of the letters ODA indicated at 3.

Various types of ink satisfy the requirements heretofore mentioned, as for example

an ink for use with ordinary paper may comprise: barium sulfate, casein, formaldehyde, water, coloring matter.

The barium sulfate serves as a whitener; the casein as a binder, and the formaldehyde as a hardener to render the mixture insoluble. Practically any suitably colored dyestuff may be used to give the ink the same general color as that of the paper. While, theoretically, the dye should be such as not to have any effect upon the emulsion, yet as a matter of fact, such a small amount of the dye is present, that no deleterious effects would be perceived with the use of any of the ordinary dyes on the average types of paper.

The various ingredients of this ink may obviously be replaced by their equivalents for the purpose specified. For example, the casein might be replaced by gelatin, or any other suitable hardener to render the ink insoluble might be substituted for the formaldehyde. With white paper, ordinary white inks may be used to advantage by adding coloring matter to them, provided the ink has such characteristics that a mark made with it is substantially invisible from the opposite side of the paper, and not glaringly or even readily noticeable on the same side as the printing, due to its having substantially the same color as the paper, and which will not materially affect the sensitized emulsion. It, of course, will be understood that the designation may be applied to the paper by using any of the well known printing appliances such as stamps, printing presses and the like, care being taken not to leave an impression in relief due to too heavy pressure. The des-

ignation applied on the paper may obviously be any suitable word, expression, picture or trade-mark.

By the term "ink" as used herein, I intend to cover any substance or mixture of substances that can be applied to paper to give a reasonably permanent record of a desired marking without injuring the paper.

I claim as my invention:

1. A photographically sensitized paper having an identifying mark thereon, comprising a paper of a given color, a sensitized emulsion on the front face and a designating mark on the rear face, said mark comprising a non-abrasive colored ink which is about the same color as the rear face of the paper and does not injuriously affect the emulsion, said mark being substantially invisible through the paper, and not readily noticeable on the same side thereof.

2. A photographically sensitized paper having an identifying designation on the back thereof comprising a thin paper of a given color, a sensitized emulsion on the front face and a printed mark on the back face, comprising a non-abrasive mixture of light colored ink and coloring matter, which does not injuriously affect the sensitized emulsion, the mark being of substantially the same color as the back of the paper, practically invisible from the front face of the paper and visible from the rear only by reflected light viewed within a limited angular range.

REINHOLD S. BECKER.
